ABSTRACT: A two-piece chair bar support comprising a support piece having three wires forming a saddle to receive and support a chair bar, said wires extending outwardly and downwardly to also support a helical wire segment on the inside of said wires, and a base having three legs, inwardly of said helical segment, each having a plurality of undulations, said helical segment engaged in said undulations and said legs interconnected at the points of upper and lower triangular frame members; said support and base pieces adjustable by relative rotation thereof with said helical strip segment in said undulations.

PATENTED JUN 22 1971

3,585,773

FIG 1

FIG 2

REINFORCEMENT BAR SUPPORT

This invention relates to means for supporting bar stock prior to its incorporation in a reinforced concrete structure. More particularly this invention relates to a chair bar support known in the trade as a high chair.

A principal object of this invention is to provide such a support which is readily adjustable in height on a job site and which is sturdy and rugged in construction in order that reinforcing materials may be located accurately in height as specified by the engineer or designer. Other objects are to provide a support which, by virtue of its adjustability minimizes the number of sizes which need to be stocked and thereby also minimizes the errors made by unskilled personnel in selecting the sizes; which is inherently stable; and, which is simple and relatively inexpensive to manufacture.

In general the invention features a two-piece construction comprising a base piece and a support piece. A saddle on the support piece is provided to support a bar. One of the pieces has a helical strip segment secured thereto. The other of the pieces has a plurality of legs each having a plurality of undulations in which the helical strip segment is rotatably engaged. Thus, relative rotation of the two pieces causes adjustment axially of the helical segment.

Other objects, features and advantages of this invention will be apparent to those skilled in the art from the following detailed description of a preferred embodiment thereof taken together with the accompanying drawing, in which:

FIG. 1 is a plan view of a high chair embodying the invention and supporting a chair bar; and

FIG. 2 is a side elevation of the high chair shown in FIG. 1.

With reference to FIG. 2 of the drawings, a chair bar 30 is supported by a two-piece high chair comprising a support piece 10 and a base piece 20. The high chair is of wire construction, the wire gauge selected depending upon the size of the high chair, heavier wire being used for larger sizes as is present practice on other forms of high chairs.

The support piece 10, as best shown in FIG. 1, comprises three wires 12, 14 extending radially outwardly from the vertical axis 32 of the support at uniform 120° intervals. The wires 12, 14 are joined adjacent the support axis 32, wire 12 positioned between wires 14. At their position of joinder the wires 12, 14 are bent to form a concave saddle 16 facing upwardly to receive and support chair bar 30. As they extend angularly downwardly. At a predetermined equal distance from the support axis 32, the wires 12, 14 are bent downwardly, parallel to axis 32. A helical wire strip segment 18 is joined to wires 12, 14 on the inner, lower portions thereof. Helical wire strip segment 18 extends slightly more than 1 revolution about the inner portion of support piece 10 being connected at two points to one wire 12 thereof but only once to each of the other wires 14 thereof.

Base 20 has three legs 22, the three legs providing excellent stability. The legs are equidistantly spaced about the support and extend vertically parallel the support axis 32. Each leg has a plurality of undulations 24 facing outwardly toward helical segment 18. Legs 22 are spaced from axis 32 adjacent helical segment 18 with segment 18 engaged in undulations 24. For production convenience, the legs 22 are identical to each other, having matching undulations 24, the helical strip segment 18 therefore having a pitch permitting it to engage the next highest undulation in each leg 22 in a three-legged structure, i.e., a pitch per revolution equal to three undulations. Legs 22 are interconnected by equilateral wire frame members 26 and 28 to which they are joined and which are triangular in shape for maximum strength. Lower frame member 26 is connected at its points to the exterior sides of legs 22 to prevent spreading and upper member 28 is connected at its points to the interior to prevent inward deflection as well as to avoid interference with support piece 10 and helical segment 18.

To assemble the support and base pieces, helical segment 18 is simply threaded onto the undulations 24 of legs 22. Vertical adjustment may then be made as desired by relatively rotating the two pieces 10, 20. It may be easier on the job site

to rotate base piece 20 rather than support piece 10 if they are already in position supporting a bar 30. To minimize the number of sizes of elements employed in a system of supports, all size variations may be vertical and may be embodied in base pieces 20, all support pieces 10 being of uniform size.

Other embodiments of this invention will occur to those skilled in the art which are within the spirit and scope of the following claims.

What I claim is:

1. An adjustable, two-piece support for bar stock to be incorporated in a reinforced concrete structure, comprising: a base piece; and, a support piece having a saddle for receiving and supporting bar stock;
- 15 one of said pieces having a helical segment of strip material supported thereon about an axis; the other of said pieces having adjacent said segment a plurality of legs spaced about said axis and parallel thereto, said legs each having a plurality of undulations therealong facing said segment; and said segment extending between said legs, having circumferentially spaced portions in slidable engagement with the undulations of each said leg, whereby said segment is rotatable relative to said legs, successive said portions in one direction progressively along said segment being in engagement with undulations of each leg located at a different axial position from the undulations engaged at adjacent legs by adjacent portions; whereby axial adjustment of said saddle is accomplished by relative rotation of said base and support pieces.
- 20 2. The support claimed in claim 1 in which said legs are part of said base piece and said segment is part of said support piece.
- 25 3. The support claimed in claim 1 in which said legs have matching undulations and the pitch of said helical segment is one undulation from one leg to the next.
- 30 4. The support claimed in claim 3 in which there are three said legs equidistantly spaced from and about said axis.
- 35 5. The support claimed in claim 4 in which said legs are part of said base piece and said segment is part of said support piece.
- 40 6. The support claimed in claim 5 in which said legs are positioned inwardly of said helical segment toward said axis and said helical segment is connected by means positioned outwardly therefrom to said saddle.
- 45 7. An adjustable, two piece support for bar stock to be incorporated in a reinforced concrete structure, comprising: a base piece; and
- 50 a support piece having a saddle for receiving and supporting bar stock;
- 55 said support piece having a helical segment of strip material supported thereon about an axis; said bar piece having adjacent said segment a plurality of legs spaced about said axis and parallel thereto, said legs each having a plurality of undulations therealong facing said segment;
- 60 said legs being positioned inwardly of said helical segment toward said axis and said helical segment being connected by means positioned outwardly therefrom to said saddle; and,
- 65 said segment in rotatable engagement with said undulations at a different axial position progressively in one direction at each leg relative to adjacent legs; whereby axial adjustment of said saddle is accomplished by relative rotation of said base and support pieces.
- 70 8. The support of claim 1 wherein each said leg comprises a segment consisting of an undulating strip providing said plurality of undulations.
- 75 9. The support claimed in claim 7 in which said legs are interconnected by frame members comprising equilateral triangular forms said legs attached at the points of said frame members.

10. The support claimed in claim 9 in which one said frame member is positioned at the base of and on the other side of

said legs and the other of said frame members is positioned at the upper portion of and on the inner side of said legs.

UNITED STATES PATENT OFFICE
CERTIFICATE OF CORRECTION

Patent No. 3,585,773

Dated June 22, 1971

Inventor(s) Albert M. Seppala

It is certified that error appears in the above-identified patent and that said Letters Patent are hereby corrected as shown below:

Column 1, line 44, after "extend" insert

--outwardly from the support axis 32, wires 12, 14 also
extend--;

Column 3, line 2, change "other" to --outer--.

Signed and sealed this 26th day of October 1971.
